UNITED STATES PATENT OFFICE.

ADOLPHUS SYLVESTER DENNIS, OF CLEVELAND, OHIO, ASSIGNOR TO THE BANKERS ADDING MACHINE CO., OF CLEVELAND, OHIO, A CORPORATION.

ADDING AND RECORDING MACHINE.

SPECIFICATION forming part of Letters Patent No. 758,052, dated April 26, 1904.

Application filed September 8, 1900. Serial No. 29,358. (No model.)

To all whom it may concern:

Be it known that I, ADOLPHUS SYLVESTER DENNIS, a citizen of the United States, residing at Cleveland, in the county of Cuyahoga and State of Ohio, have invented certain new and useful Improvements in Adding and Recording Machines; and I do declare that the following is a full, clear, and exact description of the invention, which will enable others skilled in the art to which it appertains to make and use the same.

My invention relates to improvements in adding and recording machines, and particularly to a machine on which I have two several applications in the United States Patent Office for Letters Patent, one dated March 25, 1898, Serial No. 675,063, and the other having renewal date of March 31, 1898, Serial No. 676,006.

The present invention therefore consists of certain improvements on the constructions appearing in said application, all substantially as shown and described, and particularly pointed out in the claims.

In the accompanying drawings, Figure 1 is a side elevation of the complete machine. Fig. 2 is a plan view of the machine. Fig. 3 is a longitudinal sectional elevation on line A A, Figs. 2 and 6. Fig. 4 is a longitudinal sectional elevation on line B B, Figs. 2 and 6. Fig. 5 is a central longitudinal sectional elevation on line C C, Figs. 2 and 6. Fig. 6 is a plan view of the machine on section-line D D, Fig. 4. Fig. 7 is a plan view looking down from line E E, Figs. 4 and 5. Fig. 8 is a rear elevation of the machine looking to the left from line G G, Fig. 4. Fig. 9 is a cross-section on line F F, Fig. 4, looking to the right. Fig. 10 is a front elevation, partly sectional, of the carriage and the pivoted column-determining levers therein. Fig. 11 is a cross-section of the adding-wheels proper, the totalizing-wheels and associated parts on a line corresponding to H H, Fig. 12. Fig. 12 is a cross-section of three several adding-wheels, showing their bearings, as hereinafter more fully described. Fig. 13 is a cross-section on line I I, Fig. 11, showing the totalizing-wheels

on their shaft. Fig. 14 is a perspective detail of a single totalizing-wheel out of the group in Fig. 13. Fig. 15, Sheet 4, is an elevation of the type-bar for printing the items. Fig. 16 is a cross-sectional view of the machine on a line corresponding to L L, Fig. 2, but omitting all the mechanism except that shown for automatically shifting and feeding the ribbon. Fig. 17 is a detail sectional view, enlarged, of one of the ribbon-wheels, as hereinafter more fully described. Fig. 18 is a sectional elevation of part of the mechanism shown in Fig. 16 on line J J at the left. Fig. 19 is an elevation on line K K, Fig. 16.

In the views thus shown 2 represents the frame of the machine, which carries all the other parts directly or indirectly, whether stationary or operative. The keys are represented by 3, of which there are ten in this machine, running from "0" to "9," inclusive, and in addition there is a space-key 4 to correct errors in the column work, as hereinafter described. The nine several keys are employed to write the items, whatever their size, but have nothing to do with the totalizing mechanism, which is a separate line, as will be seen farther along.

The carriage 5 rests horizontally across the top central portion of the machine, as seen in plan, Fig. 6, and in elevation, Fig. 5, and carries a number of parts, as will appear. It runs on ball-bearings on the channeled cross-rails 6 of the main frame and is under constant spring tension through the flat spring-coil 7, Fig. 7, having one end fastened to its inclosing case 8 and the other to shaft 9. A drum 10, rigid on this shaft, and a corresponding drum 11 on the opposite side of the machine, Fig. 9, are connected by endless metal tape 12, secured to the carriage 5 at one point, so that every time a key-lever is depressed to print a character the carriage is fed forward one step after the manner of a type-writer.

On the rear end of shaft 9 is a segmental ratchet 13, adapted to be engaged by two escapement-pawls 14 and 15, successively, Fig. 8. These pawls are arranged side by side on an upright rocking post 16, which has a head

17, on which pawl 15 is rigid and pawl 14 is pivoted. Normally pawl 14 engages ratchet 13, and when a key is depressed post 16 is rotated and pawl 14 carried inward out of engagement, while at the same time pawl 15 takes its place before permitting movement of the ratchet 13 and holding shaft 9 still. Meantime pawl 14 has been drawn down by its link connection to engage the next lower tooth, as will soon appear.

All the key-levers have like operations, and when any one is depressed it strikes the cross-frame 18 beneath, Fig. 5. Said frame is pivoted at both sides on cross-shaft 19, on which the keys are independently pivoted. Frame 18 has an arm 20, centrally through which the rear vertical pawl-carrying post 16 is rotated by means of rod 21, having an L-shaped head 22, and the arm 23 on post 16 having in this instance a set-screw 24 engaged by head 22 when it is forced inward by arm 20. This causes post 16 to rotate just enough to exchange pawls in engagement with ratchet 13, as above described, and this occurs every time a key-lever is depressed. The further action of pawl 14 is dependent on the movement of the printing-hammer 25, supported on arm 26, carried by shaft 27, Figs. 5 and 8. The blow of this hammer to make an imprint is dependent on spring-pressed bolt 30, which rests against short arm 31, rigid with shaft 27, said bolt being confined to operate in the casing 32, containing spring 33, bearing against the head of said bolt. Another short arm 34, rigid with shaft 27, engages the short portion of L-shaped head 22, in which is a slot 35, adapted to receive the downwardly-curved end of said arm 34 when said head is carried rearward through the action of rod 21, and shaft 27 is rotated as the hammer 25 delivers its stroke. Then as the key-lever which has caused this action rises the rod 21 is carried back by the action of its spring 36, the short arm 34 is raised out of its slot to position, as in Fig. 5, by the pull from spring 7 on shaft 9 and pawl 14 and its link 41, bolt 30 is forced back under this pull, and hammer 25 assumes normal retired place.

Now reviewing the operation of pawl 14, Fig. 8, the said pawl is pivoted in head 17 and is subject to opposite movements. Thus a bolt 40, supported in arms on the post 16, serves to hold the said pawl up in normal position to engage the teeth on ratchet 13; but being spring-pressed said pawl can be pressed back by the teeth on the ratchet to allow for the rotation of said ratchet and its shaft 9 when the carriage is set to starting position. It also has a link 41, connecting with arm 42 on shaft 27, so that when said shaft is rotated for the actuation of the hammer it will pull down the pawl 14 far enough to engage in over the next pawl below, as pawl 15 is released by swinging backward to rest instantly on release of the key-lever. Then

as pawl 14 rises to normal position it allows rotation enough of segment 13 to make a step of feed for the carriage to print in the next column. A bow-spring 14* (shown in Figs. 5, 7, and 8) returns post 16 to normal position, and then pawl 14 is engaged by a lower tooth on ratchet 13 and is carried up to the limit of its movement by the rotation of the ratchet under its own spring-power. This spaces the carriage.

Sometimes it is desirable to do spacing without operating a key-lever, as when an error in setting the carriage occurs. For this purpose I have the lever 4 apart from the key-levers proper and which is rigid with shaft 19 thereon. This particular lever has an arm 44, rigid with itself or with shaft 19, adapted to engage push-rod 45, Fig. 5, and through arm 23 on rotatable post 13 actuates pawls 14 and 15, thus affording an independent way for feeding the carriage 5. In this operation the moment pawl 14 is disengaged from segment 13 the bolt 30 is free to act and throw the hammer-arm 26 forward; but the hammer is deterred from making a full stroke by the L-shaped head 22, which now serves as a stop by reason of arm 34 striking the top of said head instead of entering slot 35; but this limited action of bolt 30 is sufficient to rock shaft 27 and pull pawl 14 down by means of link 41 and arm 42, and thus pick up the next lower tooth when post 16 is rotated to its normal position by the pressure of bow-spring 14*.

On the rear of the carriage 5 are feed-rolls 47 and 48, between which the sheet of paper printed upon is placed, a feed-spout 49 for the sheet being shown in this machine. The paper is fed upward by these rolls with the ink-ribbon 51 between it and the type-bar 52. Said bar, Fig. 15, Sheet 4, is adapted to slide back and forth in a slot in the top cross-piece 53 of the main frame to bring any called-for figure into printing position. It bears figures or characters corresponding to those on the keyboard, so that the depression of any given key brings the corresponding character on this bar before hammer 25 for impression.

A line of separate mechanism connects said bar with the key-levers, Figs. 5 and 9. Each key-lever 3 has an arm 54, projected beyond its pivot on shaft 19, engaging beneath plate 55, fixed on shaft 56. The said arms are graduated in length according to the denomination or value of the key-lever in the series, the lever having the highest numeral or character requiring the farthest throw as this machine is organized. The rotation of shaft 56 through wing 55 moves shaft 56 and the miter-gear 57 thereon, Fig. 9, which meshes with segment 58 on upright shaft 60. The said shaft 60 has an arm 61 at its upper end, Fig. 2, connected by link 62 with type-bar 52. This produces exact correspondence and selection between the characters on said bar, which are from "0" to "9" in this instance, and

the key-levers of the same value, and the selections are unerring when the right lever has been touched. Normally the cipher is opposite hammer 25, in which case the bar 52 does 5 not move to make an impression. Spring 64, connected with an arm on upright shaft 60, restores said shaft 60 to initial position after each action.

A separate back-stop is provided to limit 10 the throw of arm 61, according to the character selected on the type-bar, said stops consisting of small vertically-movable bolts 66, each adapted to shoot up in its own hole 67, Figs. 2 and 6, when called. These bolts 66 extend from under the bottom of the machine, 15 Fig. 8, to the top and are operated by the key-levers through diagonally-arranged levers 68, pivoted between their ends on the under side of the machine and engaged by rods 70 at their front ends. These rods are attached each to its own key-lever and have springs 20 about them to restore the key-levers to working position after each depression. The lower ends of said rods simply bear on levers 68, but might be pivoted thereto, and so it occurs 25 when any key-lever is depressed it throws up its corresponding back-stop bolt for the arm 61, which controls the type-bar. This makes positive what might otherwise be an uncertain 30 stop for said bar. Eight of these stops 66 are here shown, one of which, the last one at the left being a fixed stop. No stop is shown for the first movement of type-bar 52, because the momentum of the same under the 35 slight impulse of lever 1 will not carry said bar beyond alining position with hammer 25 to any perceptible degree.

The carriage 5 normally is at the left of the machine and for printing is moved toward 40 the right as many points as there are figures in the item to be printed. Thus if the sum or item be, say, 365 the carriage is carried over to point the first figure in the hundreds-column, the second in tens-column, and the 45 third in units, and the vertical thumb-levers 72, Figs. 5 and 10, particularly serve to fix the starting place for any given item, large or small. These levers are pivoted in a boxing 50 73 on the front of the carriage and have substantially right-angled projections or fingers 74 at their bottom adapted when said levers are used to engage each its own particular stop 75 on the frame below, thus preventing the moving of the carriage to the right farther 55 than the right stop will allow. Thus if the third lever from the right be engaged by the thumb to move the carriage to starting-place in hundreds-column it would engage, say, the third lug or stop 75 from the right and 60 stopping the carriage there make that the starting-point for printing that item, tens being next and units last. If the wrong lever 72 had been operated, say, to set the machine in the ten-thousand column, the spacing- 65 lever 4 can be operated to bring the machine

to the right position, and then operations begin through the key-levers. The lugs or stops 75 are staggered, and the points 74 of the levers are arranged in respect thereto so that each will engage only its own stop and none other, and all the levers are arranged to work with the spring-pressed bar 76, or they may have retracting-springs of their own, or both, as preferred, to restore them to normal position. Hence in printing an item the first 75 thing to do is to bring the carriage to the right place according to the column in which the first figure is to be printed. Then printing goes forward through the key-levers, and this operation is repeated for each successive 80 item indefinitely.

The "hammer-arm" 26, so called, Fig. 8, is really a heavy wire bow having its two extremities fixed on the shaft 27 at the sides and bottom of the machine, and the hammer 85 is adjustably secured thereon.

The foregoing mechanism mainly has to do with the printing of items, and the total or sum of the items need not be struck off if not wanted; but it has been faithfully added up 90 as each figure has been recorded and now nothing remains to be done but to strike off the total in a single line and at a single stroke by or through the totalizing-hammer. In this carrying forward of the work for totalizing 95 the items I employ a set of adding-wheels 77 and a set of total or recording wheels 78, Figs. 5 and 11, and with these the initial operating-wheel 80, through which each adding-wheel is reached by sliding wheel 80 in beneath it. There are as many or more adding-wheels as key-levers and a certain recording-wheel geared with each adding-wheel, so 100 that each lever not only works a line of mechanism to print the items, but also to add the 105 items as they are printed by carrying their sum forward with the adding and total wheels.

The wheels 77 and 78 are supported within the walls of what is termed the "stationary" head 81, Figs. 2 and 9, while wheel 80 is 110 adapted to slide on shaft 82. In this sliding movement it is controlled by a carrier-arm 83, which is fixed at its lower end to a longitudinally-sliding shaft or rod 84, Figs. 7 and 9, and this rod is connected by rigid arm 85 with the endless belt 12, attached at its top to the carriage 5. The carrier-arm 83 engages in the hub of wheel 80, so as to give a positive movement to the wheel and hold it where adjusted, but leaving the wheel free to 115 turn. Thus it occurs that wheel 80 is caused to respond to every movement of carriage 5, and by reason of this connection of arm 83 with belt 12 below the drums 10 and 11 the wheel 80 is always moved in the direction 120 opposite to the carriage. Hence if the carriage be moved by hand to the right the said wheel travels a like distance to the left, and the parts are so arranged relatively that if the carriage be set to start printing in any 130

given column the said wheel will come to the same column. This also places the said wheel in harmony with the key-levers, so that it will carry into the totals the sum called for by said levers. If the figure be, say, "5," the wheel 80 will rotate the adding-wheel 77 with which it is engaged to carry up five points, and the same with any one of the several adding-wheels to which for the time it may be 10 moved through the key-levers and carriage.

The shaft 82, carrying wheel 80, is rotated from shaft 56, Fig. 5, by segment 86 thereon engaging segment-gear 87 on shaft 82. This gear rotates loosely and carries a pawl 88, 15 which engages ratchet-wheel 89, fixed on said shaft. Hence this ratchet always holds every point moved up through segment 87.

Now referring again to the adding-wheels 77, Fig. 12, it will be noticed that they are 20 each mounted to rotate on a hub 90, rigid on shaft 91, and each hub has race and antifriction-balls about its periphery to afford an easy action for said wheels. The hubs 90 are all engaged also with the parallel rods 92, and 25 each adding-wheel has two cams 93 at its side, with ten points corresponding to ten in addition between the shoulder of each cam, and a lever 94 rides on each set of cams through a rollerbearing thereon. A dog 95 on each lever 30 94 engages with ratchet-teeth 96 on the side of the wheel 77 in the wheel next higher numerically, so that when pivoted lever 94 through its roller jumps or drops off the shoulder of a cam 93 the spring-pressed rod 97 pushes dog 95 35 forward and gives a single-point rotation to the next higher adding-wheel, thus carrying a number into said wheel. The same operation extends through all said wheels, and in this way the items are first added up into the 40 adding-wheels themselves. A spring-pressed pawl 98 engages ratchet 96 at the side of each wheel to prevent backward rotation.

In order that each higher wheel be unlocked from arm 100 when cam 93 on the 45 lower adding-wheel shall have reached the point where the carrying forward of a point is necessary, as in recording when one is added to nine, I provide each lever 94 with a side projection or pin, which in this instance comprises the extension of the pivot-pin which attaches rod 97 to lever 94. This extension of said pin bears against the vertical arm of dog 100 at a point above its pivot, and whenever cam 93 presses lever 94 back said extension releases the next higher wheel by pressing its locking-dog 100 out of engagement with the teeth on said wheel. The series of 50 higher wheels are all thus released to admit of the carrying forward of the amounts added 55 to the lower wheels.

Each adding-wheel has also a catch or dog 100, Fig. 11, which is normally engaged with the teeth thereof to keep the wheel from rotating except when required, and the said catch 60 is substantially L-shaped, pivoted at its angle

and having its short arm arranged to be engaged and depressed by roller 101 on the top of wheel-carrier 83, so that when said wheel 80 is slid on its shaft into engagement of any one of the wheels 77 the roller 101 at the same 70 time unlocks the catch 100. This liberates that particular adding-wheel for rotation, and the catch drops back as soon as the carrier is moved on. When it is desired to disengage all the catches 100 at the same time, so as to 75 enable all the adding-wheels to be alike turned to starting-point after a given task is completed, I provide a rotatable cam-shaft 104, Figs. 5 and 11, adapted to bear in the short arms of catches 100 and throw them all out 80 at once. The said shaft is turned by means of crank-lever 105, Fig. 1, gear 106 on shaft 107, and gear 108 on shaft 104. A pawl 110 on the inside of gear 108, Fig. 3, engages it with shaft 104, and thus it is rotated; but said pawl 85 can be disengaged by depressible bolt 112. This enables a total to be struck off at any time without wiping out the additions then in the adding-wheels, and frequently it is desirable that this should be done. Then the gear 90 108 will run idle, and the other chain of gears going to the paper roll for printing the total and marked 113, 114, 115, 116, and 117, successively, will operate alone, as hereinafter seen.

Referring now to Fig. 4, segment 118 on 95 shaft 104 meshes with gear 120 on adding-wheel shaft 91. Gear 118 has teeth only half-way round, which is all it requires to bring the adding-wheels back to zero, as a half-rotation of them suffices in any case, having two 100 stopping-points each at their cam-shoulders. This also gives time for the total or aggregate to be struck off through the rotation of crank 105 before the adding-wheels are set back. In this rotation of the wheels 77 to zero they 105 travel in their usual direction and are each engaged by its own pawl 121 at its side and fixed on one of the rods 92, Fig. 12.

The totalizing-hammer 123 is fixed on a vibrating frame 122, which has a lateral sliding 110 movement sufficient to carry the hammer over opposite the total-wheels to strike off any given total more or less; but it never moves farther over than to take off the total then made. This prevents printing a series of naughts beyond 115 the figures of the total, as would occur if the entire nine total-wheels were always covered. I limit this action of the hammer to the wheels used by means of a splined rod 124, Figs. 5 and 11, adapted to run in a transverse slot 120 across the edge of all the wheels 78 and which is open across all of them alike when said wheels are brought back to starting-point. When this occurs, their ciphers are all alike, exposed at the front. Of course all the 125 wheels not used to print a total remain that way. Hence the spline-rod 124 can run into all the unused ones; but this is its limit, and this I utilize to determine the movement of the hammer 123 laterally. 130

In Fig. 1 I show an inclined shaft 125, having an arm 126 at its bottom engaged with a projection on the sliding rod 127, carrying hammer-frame 122. At its top is an arm 128, connected with one end of the long spring-pressed spline-rod 124. A short arm 130 on shaft 125, Figs. 3 and 6, runs in engagement by roller with cam 131 on shaft 107 inside gear 106, and by thus rotating shaft 125 I get the necessary sweep to both arms 126 and 128, and they move together the same distance.

Hammer 123 and splined rod 124 have a simultaneous lateral movement which is dependent upon the coiled spring upon splined rod 124 and cam 131. The spring normally holds the roller of arm 130 against the high point of the cam, which keeps both hammer 123 and splined rod 124 to the extreme left until the cam is rotated. As the roller rides off the shoulder of the cam the spring presses splined rod 124 to the right, which carries the spline or key on the rod along the transverse slot heretofore described until the end of the spline strikes against the face of an adding-wheel which has been rotated and whose slot in the edge thereof has been moved out of line. Hammer 123 moves laterally the same distance as splined rod 124, and when said rod is stopped so is the hammer, which then covers only the adding-wheels upon which the total is recorded.

The hammer 123 is caused to strike by shouldered cam 133 on short shaft 134, carrying gear 113, arm 135, lying against said cam, shaft 136, carrying said arm, and another arm, 137, rigid with said shaft, Fig. 4, and bearing at its extremity against a bail 138 along the bottom of hammer-shaft 127. A heavy spring 140 presses against arm 137, and the moment arm 135 drops off the shoulder of cam 130 this spring gives an effective blow to hammer 123. Normally the said several parts are in about the relation shown in Fig. 3 ready to be moved to action. A depressible stop 142 fixes the stopping-point of crank-lever 105, through which these actuations are made.

In Fig. 4 it will be seen that there are four pins 145 in pairs above and below the shaft 50 91, on which rests yielding spring-arm 146, supported on the frame.

The totalizing or total-recording wheels 78 are loosely supported on a common shaft and have ten characters each on their periphery 55 91, equally spaced apart and corresponding teeth at their sides in mesh with the opposite adding-wheel. The two sets of wheels are so arranged that every unit added into one is carried forward into the other set, and the units, tens, hundreds, &c., are taken care of in the total-wheels through rotations from the adding-wheels.

Means for actuating the feed-rolls 47 and 48 to set the paper at the proper elevation for 65 each new line of figures to be printed consists

of a ratchet-wheel 147, Figs. 6 and 9, on the feed-roll shaft 148, which is engaged and rotated by an arm 149 on shaft 150, supported on the carriage 5, and this shaft 150 has a slotted arm at its end within boxing 73, which is rocked by a pin on bar 76 whenever a lever 72 is actuated.

When the total is to be printed, the feed-rolls are actuated to rotate first in one direction to carry the paper down slightly, so that the total will be printed in close relation to the last figure printed, and second in the opposite direction to feed the paper upward after the total has been printed to bring the same in plain view at the top of the machine. This reverse motion is attained through gears 113 to 117, Figs. 1 and 3, gear 117 having a long flat-sided shaft which extends into feed-roll shaft 148 to rotate rolls 47 and 80 85 90 95 100 105 110 In order to obtain a clear and neat print at all times, I provide automatic means actuated by the movement of carriage 5 to constantly change the inking-surface of the ribbons 51 and 170 and which causes the ribbons to feed slowly across the face of the type-bar and type-wheels first in one direction and then in the opposite direction. Different shades or colors of ribbons are used, so that the items will be printed in one shade and the totals in another. These ribbons are wound over spools 171, supported at the top and at each side of the frame 2, and pass from one spool to the other across the face of the type-bar and the type-wheels. Spools 171 are splined to vertical shafts 172 and caused to alternately rotate in opposite directions when the ribbon is unwound entirely upon either of the spools. The vertical shafts 172 are slidingly mounted in arms on the frame 2 and have each a pin 173, adapted to engage a notched sleeve or collar 174, rotatably held in arm 175. This collar has a beveled gear 176 meshing with beveled gear 177 on cross-shaft 178. This shaft has a larger beveled gear 179 meshing with a gear 180, that is actuated through suitable gearing from spring-tension carriage-operating shaft 9'. Only one of the pins 173 is in engagement with a notched sleeve 174 at a time, and it is by releasing and relocking these sleeves for each shaft 172 that the said shafts are made to reverse. This is accomplished by means of the cross-rod 190, having the arms extending at opposite sides of the center at the ends and which engage the lower extremities of the vertical shafts 172 and being in constant touch therewith. On each shaft 172 are the gears 181, which mesh and have a sliding movement with gears 182 on the vertical screw-threaded shaft 183, mounted to rotate in the frame at the side of shaft 172. A nut 184 on each shaft 172 has an extension which bears at certain intervals upon a spring 185, resting on a collar on said shafts. As shaft 172 rotates screw-threaded shaft 183 is also rotated and causes the nut to travel up or down. As shown, the nut 184 at the right side of the machine is caused to travel down while the nut at the left goes upward. The nut coming down engages spring 185 and gradually compresses it, and if nothing were to hold the shaft 172 in raised position pin 173 would drop into notched sleeve 176. This is permitted only when the ribbon 55 on spool 171 at that end of the machine has been unwound and reached the end of its travel where fastened to the said spool. Each spool is provided with a pivoted catch 187, having a spring to press the free end outward, and also 60 having a separate spring-pressed bolt 188, which rests in the groove 189 near the top of shaft 172—that is to say, in that particular shaft which is temporarily to be held in raised position. The ribbon 170 bears against the free end 65 of catch 187 and normally holds the same back and its bolt 189 in locking engagement until the ribbon has entirely unwound itself. This frees the catch, and its spring forces it outward and withdraws the bolt from groove 189, allowing spring 185 to press shaft 172 down 70 and lock pin 173 with sleeve 175. The lower extremity of shaft 172 forces down the arm on cross-rod 190 and rocks this sufficiently to cause the arm at the other end to force shaft 172 at the left up, thus freeing its locking-pin 75 connection with sleeve 175 at that side. As this shaft 172 is raised it is held in that position by bolt 188, entering shaft-groove 189, until the ribbon at that side is unwound, these movements being automatically controlled 80 on each side of the machine and the ribbons being fed in reverse direction at long intervals.

Now as an example in operation suppose that two items—"824" and "598"—are to be printed and added together, in which the total 85 is "1422." Having set the machine to start printing in the third or hundreds column and striking the key-lever 8 for the first item, an imprint of said figure will be taken from the type-bar in the item-line, and the hundreds-adding wheel will be turned up eight points with a corresponding movement of the opposite totalizing-wheel. Then having printed the figures "2" and "4" of this item in their columns there will be "824" represented 90 in both the adding-wheels and the total-wheels, which latter are an expression of the value in the "adding-wheels" and also an imprint of "824" on the paper from the type-bar. Then after recording the next item, "598," in like manner and really having "1422" in these wheels the hundreds-wheel necessarily is carried three points past the ten therein, and one point is turned forward in the thousands-wheel at its left. The further addition increases the totals in all three wheel-columns and carries forward another hundred in the hundreds-column. It has also occurred in the units-column that one ten has been taken out and carried forward in the 100 tens-column, leaving two therein, while one ten has been taken out of the tens-column and carried forward into the hundreds, leaving two therein. Now referring to the totalizing-wheels it will be found that they have been 105 rotated to correspond exactly to the results in the adding-wheels and that when the total is struck therefrom it will show up "1422," the sum of both items.

The recording-wheels are so called by reason of their serving to give the record in print, and their values are always the same as those of the adding-wheels, which they represent.

What I claim is—

1. In a typographical adding-machine, the 115 combination of the adding-wheels having printing characters thereon, the key-levers and the selecting and operating mechanism connecting said levers with the adding-wheels, a laterally-sliding item-printing bar arranged 120

above said printing adding-wheels, mechanism between said item-printing bar and each key-lever to give a varying movement to said bar, a laterally-movable total-striking hammer, and an item-printing hammer, substantially as described.

2. The combination of adding-wheels and an initial operating-wheel therefor, a series of selecting key-levers and mechanism operated

10 thereby to rotate said operating-wheel varying distances, a stop for the adding-wheels, and independent means connecting each lever with said stop and to limit the rotation of the adding-wheel thus engaged, substantially as described.

15 3. The adding-wheels arranged side by side, a single initial operating-wheel rotatably and slidably mounted to engage any one of the adding-wheels at a time, ratchet mechanism

20 to rotate said operating-wheel, a series of key-levers having operating-arms of varying lengths operatively connected with said ratchet mechanism and serving to turn the operating-wheel varying distances, a stop for

25 said adding-wheels supported to slide with said operating-wheel, and separate operating mechanism connecting each lever with said stop to cause the movement of the operating and adding wheels to correspond to the movement of the lever actuated, substantially as described.

30 4. In a typographical adding-machine, the adding and printing mechanism, in combination with a laterally-slidable striking-hammer

35 and means to set the hammer to the width of the columns added, and a line of mechanism to actuate said hammer, substantially as described.

40 5. In a typographical adding-machine, a set of recording-wheels, a laterally-slidable total-recording hammer, and means to set the hammer to the width of the columns added, said means comprising a laterally-slidable frame carrying said hammer and width-determining mechanism engaging the last rotated recording-wheel, substantially as described.

45 6. In a typographical adding and recording machine, a total-recording hammer and a laterally-slidable support therefor, a shaft and means to rotate said shaft, and an arm actuated by said shaft and engaged with said support for the hammer to fix its position, substantially as described.

50 7. In a typographical adding-machine, the adding, recording and printing mechanism, and a series of key-levers connected therewith to print the items and total, in combination with paper-feed rollers and means connected therewith to feed the paper in opposite directions successively before and after the total is printed, substantially as described.

55 8. In a typographical adding-machine, the combination of the adding and total-printing wheels with an item-printing mechanism and a series of key-levers operatively connected

therewith to print the items and to operate the adding and total-printing wheels, a movable carriage and paper - feed rollers mounted thereon, and a crank-controlled train of mechanism to strike off the total and return the adding and printing wheels to starting position and actuate said feed - rollers, substantially as described.

60 9. In a typographical adding-machine, the adding, recording and total-printing mechanism and separate item-printing mechanism, a series of key-levers and connections to actuate both said item and totalizing mechanism, a movable paper-carrier and feed, and a crank and train of gears and cam-operated mechanism to print the total, return the adding mechanism to starting position and feed the paper when the crank is rotated, substantially as described.

65 10. In a typographical adding-machine, the adding and total - printing wheels, separate item-printing mechanism, a series of key-levers to actuate said wheels and item-printing mechanism, a paper-carrier and feed-rollers therefor, separate hammers to print the items and total, means to set the totalizing-hammer in position to print only the number of columns added, means to return the adding and recording wheels to starting position after the total has been printed, and means to set and actuate said totalizing-hammer, to feed said paper, and to return the adding-wheels to starting position in a single continuous operation, substantially as described.

70 11. In a typographical adding-machine, the combination of the adding and printing wheels, a slidable item-printing type-bar, a series of key-levers and connecting mechanism to operate said wheels and type-bar, a total and an item striking hammer, a series of movable stops to limit the movement of said bar, and mechanism between said stops and key-levers whereby when a key-lever is depressed a corresponding stop is moved in the path of said bar, substantially as described.

75 12. In a typographical adding-machine, the adding and total-printing wheels, the slidable item type-bar, the item and total printing hammers, a series of key-levers corresponding to the characters on said bar, means connected therewith to rotate said wheels, a set of vertical movable bolts to limit the movement of said bar, and operative connections between said bolts and the key-levers, substantially as described.

80 13. The main frame and the slidable carriage thereon, drums at the sides of the carriage and a ribbon fixed thereto and running over said drums, in combination with a slidably-mounted initial operating-wheel for rotating the adding-wheels and an arm fixed to said ribbon and engaging said operating-wheel to slide it to working position corresponding to the position of the carriage, substantially as described.

85 14. The initial operating - wheel slidably

mounted, the carriage and a ribbon for moving the carriage, and an arm on said ribbon engaging said wheel, levers on the front of the carriage to fix the starting position to print, and a series of adding-wheels corresponding to said levers and arranged to be engaged by the initial operating-wheel, substantially as described.

15. The initial operating-wheel slidably mounted, the carriage and an arm operatively connected therewith engaging said wheel and determining its working position and a lever pivoted on said carriage to fix the column of initial operation, in combination with the type-bar for printing the items, a printing-hammer and a key-lever operatively connected with said type-bar and with said hammer to cause both said parts to act in immediate succession, substantially as described.

16. The carriage and means to fix the starting-point thereof, the initial operating-wheel and means operatively connecting the same with the carriage and adding-wheels arranged to mesh successively with said operating-wheel, in combination with a type-bar slidably mounted, the key-levers and means operatively connecting said levers with the carriage and with the initial operating-wheel and the type-bar, said means constructed to give varying movements to the said parts according to the value of the key-lever, substantially as described.

Witness my hand to the foregoing specification this 31st day of July, 1900.

ADOLPHUS SYLVESTER DENNIS.
